UNITED STATES PATENT OFFICE

2,092,673

WINDOW VENTILATOR

Steven S. Kempf, Chicago, Ill.

Application June 26, 1935, Serial No. 28,542

2 Claims.

(Cl. 98—99)

My invention relates to window screens, and my main object is to provide a screen which combines the features of a ventilator, fly screen and protector against rain and wind.

5 A further object of the invention is to build the novel screen in a self-contained unit of a compact nature, whereby to be easy to handle.

10 A still further object of the invention is to utilize the transparent property of glass or similar material for the ventilating feature of the screen, so that a maximum amount of light is admitted.

15 Another feature of the invention is to construct the same along lines of utmost simplicity and ready adaptability to conventional window installations.

20 With the above objects in view, and any others which may suggest themselves from the description to follow, a better understanding of the invention may be gained by reference to the accompanying drawing, in which—

Figure 1 is an external elevation of the novel screen;

Figure 2 is an internal elevation thereof;

25 Figure 3 is an enlarged fragmental section on the line 3—3 of Fig. 1;

Figure 4 is a fragmental section on the line 4—4 of Fig. 3;

30 Figure 5 is a fragmental view similar to Fig. 3 and illustrating a modification; and

Figure 6 is a fragmental section on the line 6—6 of Fig. 5.

35 Referring specifically to the drawing, it will be noted that I employ a frame 10 for the novel screen, which simulates in every respect the conventional screen frame used for the windows of dwellings, apartments, etc. Also, I employ a composite frame 11 of moldings to secure the sheet 12 of fly-netting to the frame 10 by screws 40 11a. However, I apply the fly-netting sheet to the back or inner side of the frame instead of to the outer side thereof as is the usual practice.

45 The ventilator feature of the novel screen is disposed frontally of the netting 12 in the form of a series of oblique visor-type vanes 13 of glass or other transparent material. These vanes occur in vertically spaced order, and are of an angle approximately as shown in Fig. 3, so that they overlap, whereby to permit air to enter but 50 check cross-drafts.

The vanes 13 are of the same angle and so mounted as to maintain their positions permanently and be held against sliding out of the frame. Thus, the side rails of the frame 10 are 55 grooved as indicated at 10a to seat the terminal

portions of the vanes 13. As noted in Fig. 4, the ends of the vanes converge in an outward direction, and the grooves 10a are formed to suit, so that when the vanes have been inserted into the frame from the rear, they cannot advance beyond their proper position as indicated in Fig. 4. The vanes are thus supported and locked in position without the use of a special fastening means. Fig. 4 shows that the netting 12 and molding frame 11 form a check for the recession of the 10 vanes.

5 While my main embodiment employs a series of fixed ventilator vanes, it is conceivable that a modification can be designed to make the vanes foldable or adjustable, as in Venetian blinds. 15 Thus, a specimen of such a modification is suggested in Figs. 5 and 6, it being noted that the vanes are mounted between pairs of disks 14, the latter having trunnions 14a journaled in the screen frame. A wire rod 15 in back of the 20 screen makes connections 15a with each of the disks, so that when the rod is lowered, the vanes swing up, and vice-versa. As mentioned, the illustration is but for purposes of example, since other methods may be devised to put the principle in practise.

25 It will be seen from the above description that I have provided a self-contained screen which has several advantages. First, it utilizes the conventional full sized fly-netting for complete protection against insects. Second, it has a set of visor-like ventilator vanes to permit ventilation without drafts and imparting an attractive appearance to the screen. Third, the ventilator vanes are transparent, and therefore permit complete passage of light and ventilation, while offering full protection against the entry of rain, snow, hail or dust. Fourth, the article is simply built, easily handled and capable of being applied to the conventional window installation by any of 40 the methods now in use. When the novel screen is of greater than ordinary width, I propose to relieve the strain at the center of the ventilator vanes by inserting a vertical support or brace preferably along the rear edges of the vanes, so 45 that these may not sag and be subject to strain or breakage. Finally, it is evident that the novel screen is made up of few and substantial parts, and may be manufactured at reasonable cost and given such ornamental value for purposes of attraction as the imagination may dictate. Its use may also extend in shorter form as a window insert, or in smaller form for automobile windows.

50 I claim:

55 1. A window ventilator comprising an open

frame, and a set of visor-type vanes mounted therein in vertically-spaced order, the vanes and frame having cooperative formations to wedge the vanes in the sides of the frame when the vanes are inserted therein

5 2. A window ventilator comprising an open frame formed with a vertically-spaced series of

grooves on the inner side of each side piece, both series of grooves converging from one face of the frame to the other, and a set of visor-type vanes arranged to seat endwise in pairs of the grooves, the ends of the vanes being convergent to become wedged in the grooves.

STEVEN S. KEMPF.
